CLAIM

The ornamental design for a mounting rail connector as shown and described.

DESCRIPTION

FIG. 1 is a front perspective view of a mounting rail connector showing our new design;

FIG. 2 is a rear perspective thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The safety helmet, mounting rails and the fasteners shown in broken lines are provided for environmental purposes and forms no part of the claimed design. The remaining broken lines depict portions of the mounting rail connector that form no part of the claimed design.
